F. CUCINOTTO

GAME APPARATUS

Filed Jan. 11, 1928

Inventor
FRANCESCO CUCINOTTO

By his attorney Alexander C. Monoffit

UNITED STATES PATENT OFFICE.

FRANCESCO CUCINOTTO, OF NEW YORK, N. Y.

GAME APPARATUS.

Application filed January 11, 1928. Serial No. 246,060.

This invention relates to games, and particularly to games of the type characterized by a rotatable member carrying numbers or other devices adapted to designate different values to be selected by the player, in combination with a stationary pointer or index device adapted to be placed near the path of the first named devices as they move around when the player spins the rotating member, so that the index device will indicate the one of said numbers which is to score when the rotating member stops its rotation, the player being entitled to score that number if he has guessed correctly the number which will be nearest the index device.

An object of the invention is to provide a game apparatus of the aforesaid character in which the rotating member and its number-carrying members, and also the index device, are of novel and attractive form, and in which the means for operating the apparatus are of such a character as to avoid easy selection of a winning number, and at the same time to make it possible for each player to have a fair and equal chance in making his selection while the apparatus is in motion.

The above, and other objects of the invention, are illustrated and described fully in the accompanying drawings and specification and are pointed out in the claims.

In the drawings, the figure shows in elevation, partly in section, a now-preferred form of game apparatus in which the invention is embodied.

In the illustrated embodiment, the part designated by the reference numeral 1 is a hollow column, mounted upon a base 2 which is supported by a table 3, the standard 4 of which is preferably hollow, as indicated.

At the top of the column 1 is mounted a disc or member 5 supported on anti-friction bearings 6 in position to rotate freely in a horizontal plane when spun by hand.

This rotating member carries a series of index members *a*, preferably bearing numbers, as illustrated, which designate the numerical values respectively assigned to each, the members *a* being suitably supported from the periphery of the disk 5, preferably dangling on flexible cords or chains *a*¹, so that they swing freely as the disk spins.

In further pursuance of the invention, an indicator device *b* is provided, which is adapted to be placed in the path of the dan-

gling index members *a*, aiding, by engagement therewith, to bring the disk to a standstill gradually, and any suitable means may be provided to support this indicator device 60 in the desired position.

In accordance with another object of the invention, the supporting means preferably is adapted to permit the indicator device *b* to be moved out of the path of the dangling index members *a* before the player spins the disk 5, so that the disk may be caused to rotate with relative rapidity before the indicator acts upon the index members, the object of this being to prevent the player 70 from controlling the movement of the disk, as the general purpose of the game is to have one or more players guess the number which will stand nearest to the indicator device *b* when the disk comes to a standstill, as 75 for example the number 7 in the instance illustrated.

A now-preferred form of supporting means is illustrated in the form of a carrier *b*¹ for the indicator device *b*, this carrier being 80 mounted on a flexible cable or chain *b*² which runs over a pulley *b*³ mounted in the wall of the column 1 and then extends downwardly through the column to a windlass *b*⁴ concealed within the base 2, and from 85 which another cable or chain *b*⁵ extends down into the tubular standard 4, having a weight *b*⁶ of suitable size to cause the windlass to wind on the cable *b*², when released, and thus raise the carrier *b*¹ to the position 90 shown, in which the indicator device *b* is in the path of the swinging index members *a*.

As a suitable form of means to draw up the weight *b*⁶ and permit the cable *b*² to unwind, allowing the carrier *b*¹ to descend with the indicator device, out of the path of the dangling index members *a*, the windlass is provided with a crankshaft *b*⁷, extending out through the wall of the base 2, so that the operator of the game can turn the windlass *b*⁴, winding up the cable *b*⁵ and thus elevating the weight *b*⁶, at the same time permitting the descent of the indicator device *b* as the cable *b*² unwinds from the windlass, and when the operator removes his hand from the crank *b*⁷, a spring-pressed brake *b*⁸, which bears against the barrel of the windlass at *b*⁹, tends to hold the windlass with the weight *b*⁶ in the elevated position indicated by dotted lines. 100

In this position, the apparatus is ready for play, and then the operator spins the

disk 5 rapidly, and presses a button b^9 which releases the brake b^8 and thus permits the weight b^6 to turn the windlass b^4 winding on the cable b^2 and drawing the indicator device b up into the path of the swinging index members a , so that the motion of the latter is gradually arrested as already described, and the player who has guessed correctly the number 7 is credited with that score.

It is preferred to make the indicator device b in the form of a flag, as illustrated, and also to make the carrier in the form of a mannikin, since this imparts a lifelike and attractive appearance to the game, and draws the attention of prospective players, when the game is in action, the mannikin carrying up the flag b with a jump, which also serves the purpose of avoiding conscious selection of a number by any player, or by the operator, as the players can make their selections of numbers while the disk 5 is still rotating rapidly before the flag b is carried into the path of the swinging index members a .

If desired, the flag b may be so arranged that the dangling index members a will be caused to swing by centrifugal force, at the beginning of rotation of the disk, in a path outside that in which the flag b is placed, so that the difficulty of consciously selecting a winning number will be increased, the selections of numbers being required before the disk 5 rotates slowly enough to permit the dangling members a to swing in the path in which stands the indicator device b .

The manner in which the members a are connected to their individual flexible holders a also permits them to turn about their vertical axes readily, when they engage the flag b in passing, so that the retarding effect of the flag is very gradual, and this rotation of the index members a prevents the players from reading the numbers easily until the disk slows down considerably, this arrangement enhancing the uncertainty of selection, and imparting a pleasing element of suspense as to the outcome of the play.

I claim:

1. A game apparatus characterized by a rotor having a series of dangling members adapted to be carried around in a circular path by said rotor, and characterized further by an indicator device adapted to be moved into the path of said dangling members to arrest their circular movement gradually, means tending to move said indicator device automatically into said arresting po-

sition, manually operated means to move said indicator device at times out of said arresting position, and a controlling device to control said movements, said controlling device being adapted for operation manually to release said means for moving said indicator device into said arresting position. 60

2. A game apparatus characterized by a rotor having a series of dangling members adapted to be carried around in a circular path by said rotor, and characterized further by an indicator device adapted to be moved into the path of said dangling members to arrest their circular movement gradually, means tending to move said indicator device automatically into said arresting position, manually operated means to move said indicator device at times out of said arresting position, and a controlling device to control said movements, said controlling device being adapted for operation manually to release said means for moving said indicator device into said arresting position and 75 said latter means being adapted to cause a rapid movement of said indicator device to said arresting position. 80

3. A game apparatus characterized by a rotor having a series of dangling members adapted to be carried around in a circular path by said rotor, and characterized further by an indicator device adapted to be moved into the path of said dangling members to arrest their circular movement gradually, a flexible member and a windlass therefor adapted to draw said indicator device into said arresting position, a weight having a flexible member also adapted to be wound upon said windlass in such a manner that when said weight descends it turns said windlass to draw said indicator device into said arresting position, means to permit said windlass to be turned manually to wind up said weight, a device adapted to control rotation of said windlass by said weight, and means to release said controlling device at times to permit said weight to cause movement of said indicator device to said arresting position. 95 100 105

4. A form of the game apparatus as in claim 2, in which said indicator device includes a mannikin carrying a flag and adapted to move with a jump toward the path of movement of said index members. 110

In testimony whereof, I have signed this specification.

FRANCESCO CUCINOTTO.
